UNITED STATES PATENT OFFICE.

JOHN B. OYER, OF GRIDLEY, ILLINOIS.

GRAIN-WEIGHING MACHINE.

SPECIFICATION forming part of Letters Patent No. 371,148, dated October 4, 1887.

Application filed April 18, 1887. Serial No. 235,207. (No model.)

To all whom it may concern:

Be it known that I, JOHN B. OYER, a citizen of the United States, and a resident of Gridley, in the county of McLean and State of Illinois, have invented certain new and useful Improvements in Grain-Weighing Machines; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of my improved grain-weighing machine. Fig. 2 is a front view of the same. Fig. 3 is a bottom view; and Fig. 4 is a transverse sectional view on line *x* *x*, Fig. 3.

Similar numerals of reference indicate corresponding parts in all the figures.

My invention has relation to that class of grain-weighing machines in which the grain is filled into receptacles, which are tilted when filled with a certain quantity of grain, emptying the filled receptacle, and bringing an empty receptacle before the discharge-spout; and it consists in the improved construction and combination of parts of such a weighing-machine, as hereinafter more fully described and 30 claimed.

In the accompanying drawings, the numeral 1 indicates the spout from which the grain is discharged, and which in this case is shown extending from the upper end of an elevator, 35 2, of the usual construction.

Suitable obtuse V-shaped brackets, 3 and 4, are supported under the spout—one, 3, being secured to the elevator-casing, while the other, 4, is supported by means of braces 5 forward 40 of the same, registering, however, with it, and the ends of the brackets are connected by means of suitable strips or bars, 6.

A board or plate, 7, is secured at its middle to a shaft, 9, having its trunnions 8 journaled in suitable bearings, 10, in the V-shaped brackets, and semicircular side pieces, 11, are secured to the edges of this bottom-board, having a partition, 12, secured between the side pieces upon the middle of the bottom, standing at right angles to the same.

A scale-beam, 13, is secured at its ends in

brackets 14 to the under side of the bottom of the receptacles, and a poise, 15, slides upon this beam, and may have its throw upon the same adjusted by means of blocks 16, sliding 55 adjustably upon the beam, and having set-screws 17 for securing them, suitable graduations being made upon the scale-beam to indicate at which weight the receptacle opposite to the sliding poise bearing against the adjustable block will be depressed, causing the poise to slide to the opposite end of the beam, counterbalancing the other receptacle.

Longitudinally-slotted arms 18 are secured to project downward from the apices of the obtuse V-shaped brackets, and V-shaped abutting brackets 19 have nutted bolts 20 sliding adjustably in the slots and inserted through their apices, securing the abutting brackets. The ends of these brackets are bent to form 70 suitable abutments for the bottom of the tilting receptacles, one end of the bottom striking one pair of arms of the V-shaped brackets at each time the receptacles are tilted, and by adjusting the said abutting brackets higher or 75 lower in the slotted arms the receptacles may be allowed to tilt less or more, as desired. The outer trunnion of the tilting receptacle is provided with a disk, 21, and two pawls, 22, are pivoted with their ends to diametrically-opposite pins 23 upon the disk, having 80 springs 24 bearing from above against them, and having their ends engaging two ratchet-rims, 25, upon a disk or wheel, 26, journaled within a suitable glass-covered casing, 28. 85 The ratchet-rims of the disk are separated by a smooth flange, 27, and the pawls will as the receptacle is rocked revolve the disk the space of one tooth each time, so that by suitable inscriptions and indices the number of times the 90 receptacles is tilted to either side may be registered, the ratchet-disk having a long tooth, 29, which engages with another ratchet-disk, 30, which registers the tens, and which disk 30 is provided with a long tooth, 31, which 95 engages the teeth of a ratchet-disk, 32, which registers the hundreds, so that the number of times the receptacle has been tilted is registered, and consequently the number of the 100 quantities of grain contained in each compartment of the receptacle.

It will be seen that by adjusting the blocks

upon the scale-beam the throw of the poise may be adjusted, and when one compartment of the receptacle is filled with sufficient grain to counterbalance the poise the receptacle will be tilted, emptying the grain out of the filled receptacle and causing the poise to slide to the overbalanced side, causing it to keep the empty compartment under the spout to be filled, while the full compartment is emptied and may again be tilted up under the spout when the compartment now being filled is filled.

Having thus described my invention, I claim and desire to secure by Letters Patent of the United States—

1. In a grain-weighing machine, the combination of a grain-spout, a receptacle consisting of a bottom pivoted upon a transverse shaft below the spout, and two semicircular side pieces and a partition between the same at right angles to the bottom, and a scale-beam upon the under side of the bottom, and provided with a sliding poise and with adjustable stops for the same, as and for the purpose shown and set forth.

2. In a grain-weighing machine, the combination of a grain-spout, two frame-pieces secured below the spout, a bottom pivoted with the trunnions of a transverse shaft in the middles of the frame-pieces rocking transversely to the spout, and having semicircular side pieces and a transverse partition at right angles to the bottom, a scale beam secured upon the bottom and having a sliding poise and stops for the same, longitudinally-slotted bars project-

ing downward from the middles of the frame-pieces, and V-shaped abutment-brackets secured adjustably to the slotted bars by nutted bolts at their apices, and having bent ends at their arms forming abutments for the bottom when tilted to either side, as and for the purpose shown and set forth.

3. In a grain-weighing machine, the combination of a grain-spout, two frame pieces secured below the spout, a receptacle consisting of a bottom pivoted with the ends of a transverse shaft in the middles of the side pieces, and having two semicircular side pieces and a partition secured to the middle of the bottom at right angles to the same, a scale-beam secured longitudinally to the bottom and having a sliding poise and adjustable stops for the same, longitudinally-slotted bars at the middles of the frame pieces, V-shaped abutting brackets secured with nutted bolts at their apices in the slots, and having the ends of their arms bent to form stops for the tilting bottom, a registering device composed of ratchet-disks, and a disk upon one end of the rocking-shaft, having two spring-pawls pivoted to it engaging one of the disks of the registering device, as and for the purpose shown and set forth.

In testimony that I claim the foregoing as my own I have hereunto affixed my signature in presence of two witnesses.

JOHN B. OYER.
